UNITED STATES PATENT OFFICE.

JAMES LAWSON, OF BELLAIRE, OHIO.

DESIGN FOR A CASTER.

SPECIFICATION forming part of Design No. 19,438, dated November 19, 1889.

Application filed October 17, 1889. Serial No. 327,375. Term of patent 3½ years.

To all whom it may concern:

Be it known that I, JAMES LAWSON, a citizen of the United States, residing at Bellaire, in the county of Belmont, State of Ohio, have 5 invented and produced a new and original Design for Casters, of which the following is a specification, reference being had to the accompanying drawings, forming part thereof.

Figure 1 is a perspective view of a caster 10 illustrating my design, and Fig. 2 a side elevation of the same.

The principal feature of my design consists in a support for the upper and lower sections of a caster made in the shape of a 15 Maltese cross, and in making the upper section in the shape of a Maltese cross, so as to make the completed article a very attractive and salable one.

A represents the lower section of the 20 caster, which is square in its general contour, with rounded edges. This lower section is supported on standards, which are a repre-

sentation of a paw grasping a sphere. The upper section of the caster B is made in the shape of a Maltese cross, and is provided with 25 circular openings therein for the entrance of the bottles. This upper section is upheld by a number of supports D D, which are of the shape of a Maltese cross and which connect the two sections. The upper section is further supported by means of a central standard E, formed at its top with a loop for holding the article. 30

What I claim as new, and desire to secure by Design Patent, is—

A design for a caster, as described and shown.

In testimony whereof I affix my signature in presence of two witnesses.

JAMES LAWSON.
